UNITED STATES PATENT OFFICE.

RUSSELL HUFF, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

IGNITION APPARATUS FOR HYDROCARBON-ENGINES.

1,079,413.

Specification of Letters Patent.

Patented Nov. 25, 1913.

Application filed December 22, 1906. Serial No. 349,190.

To all whom it may concern:

Be it known that I, RUSSELL HUFF, a citizen of the United States, and resident of Detroit, Wayne county, State of Michigan, have invented certain new and useful Improvements in Ignition Apparatus for Hydrocarbon-Engines, of which the following is a specification.

This invention relates to electric ignition apparatus for multiple cylinder hydrocarbon engines and more particularly for engines adapted for driving motor vehicles and motor boats.

The invention will be described in connection with the accompanying drawing in which,

Figure 1 is a side elevation of a magneto generator illustrating the present invention; Fig. 2 is a left end elevation of the generator 20 showing the switching and contact devices; Fig. 3 is a section on the line 3 of Fig. 2; Fig. 4 is a section on the line 4 of Fig. 2; Fig. 5 is a section on the line 5 of Fig. 2; Fig. 6 is an enlarged view of the lower part 25 of Fig. 2; Fig. 7 is a plan view of the devices shown in Fig. 6; Fig. 8 is a diagrammatic view illustrating the cylinders of the hydrocarbon engines and the various circuits.

Referring to the drawing 10 indicates the 30 permanent magnets of the magneto generator A, and 11 the armature shaft. The armature may be of any desired type, such, for instance, as that illustrated in Letters Patent No. 780,221 to J. W. Packard. Upon 35 the face of the generator is a fixed plate 12 upon which is mounted a face plate 13. The armature shaft passes through the plates 12 and 13 and the plate 13 is arranged to rock about an axis concentric with the shaft. As 40 shown the plate 13 is provided with a circular in-turned lip 14 which engages a circular groove in a bracket or projection of the plate 12. The current generated by the magneto passes through a terminal 15 to a 45 contact 16 on the end of the armature shaft, thence to a brush 17 bearing on said contact and to a bracket 18 which carries a spring 19 bearing on the brush 17. The bracket 18 is carried on but insulated from two posts 50 20, 21, fixed in the face plate 13. Bracket 18 carries a suitable spring-supported contact 22 adapted to coöperate with a contact 23 carried by a cam lever 24. Lever 24 is pivoted on a post 25 fixed in the face plate 13.

One arm of the lever bears a pin or roller 26 55 running in a cam groove in the face of a cam wheel 27 fixed on the armature shaft 11 (Figs. 2, 4, 6 and 7). The post 25 carries a brush 28 bearing on the cam wheel 27 and the cam wheel and lever 24 are "grounded" 60 on the armature shaft. When the points 22 and 23 are in contact the armature is short-circuited and when the contact is broken the current in the armature circuit is forced to pass out through binding post 29 on the 65 bracket 18, through conductor 30, through the primary coil of a transformer 31 and back to armature shaft by way of post 21. The secondary circuit of the transformer will be referred to hereinafter. 70

Upon the posts 20, 21, and insulated therefrom, is supported a bracket 32 carrying a spring contact point 33 similar to the point 22. Coöoperating with the point 33 is a contact point 34 carried by a cam lever 35 pivoted on a post 36 upon the face plate 13. A spring 37 tends to move the points 33, 34, apart and to press one arm of the lever upon a face cam on the periphery of the cam wheel 27. When the points 33, 34 are in contact, 80 the current from a battery 38 passes through conductor 39, the primary coil of the transformer 31^b, binding post 21, face plate 18, cam lever 35, bracket 32, post 40 and conductor 41. It will be understood that the 85 magneto current is only available when the motor is operating, the magneto being driven from the motor and at the same speed as the motor. For starting the motor the battery current is used. The primary circuits of the battery and magneto are provided with suitable switches as shown in my prior Patent 838,251, Dec. 11, 1906.

The secondary or high tension circuit from the transformers 31 and 31^b passes through 95 conductors 43, 43^b respectively to a switch 43^c and thence through conductor 43^d to a post 44 on a distributor plate 45 of insulating material which is mounted on the magneto above the face plate 13. From the post 100 44 the high tension circuit passes through a conductor 46 to a conducting ring 47 on the distributor plate. Concentric with the ring 47 is a shaft 48 which is mounted on the magneto and driven from the armature shaft 11 by gears 49, 50, the latter having twice as many teeth as the former and driving the shaft 48 at one-half the speed of the arma-

ture shaft. On the shaft 48 is an arm of insulating material 51 carrying a plate 52 of conducting material.

Mounted in the plate 52 is a brush 53 which is constantly in contact with the ring 47 and another brush 54 which is adapted to make contact with four segmental plates 55 upon the distributor plates, which plates 55 are respectively connected by conductors 56 with binding posts 57. From the posts 57 the conductors 58 lead respectively to the spark plugs S of the motor cylinders E. One element of each spark plug is grounded on the engine and the circuit returns from the engine to the transformers 31 or 31^b through conductor 59.

Circuit breakers 23 and 34 are operated twice during each rotation of the armature shaft and, therefore, four times during each 20 rotation of the distributor shaft 48, and the cams are arranged to break the circuits at times when the brush 54 is in contact with one or other of the plates 55. In order that the spark may be advanced or retarded with 25 respect to the position of the piston in the cylinder at the time of explosion, I arrange the face plate 13 so that it may be rocked in either direction as indicated by the dotted lines in Fig. 2. Thus, assuming that the 30 magneto is turned in the direction of the arrow, Figs. 2 and 6, the spark will be advanced by rocking the right end of the face plate upward and will be retarded by rocking it downward, the extreme positions being 35 shown in dotted lines in Fig. 2. Ignition may occur when the brush 54 is at any point upon one of the curved contact plates or segments 55. If the face plate 13 is set in a position to cause late or retarded ignition, the high tension current will flow 40 through the brush 54 and contact segment 55 just before the brush leaves the segment and the cam 27 may prolong the primary current after the brush has left the segment. This 45 will result in a great difference of potential between the brush and the segment, which would tend to cause a spark to leap from the brush to the next succeeding segment across which it is to rub and thus cause pre-ignition. 50 and a "back kick" in the cylinder having its spark plug connected with said succeeding segment. To avoid this a safety device in the form of a finger 60, connected electrically with the plate 52, is mounted on 55 the arm 51, which finger trails after the brush 54. The finger 60, as shown in Fig. 1, has its point close to but not in contact with the face of the distributor plate, there being an air gap 61 between the finger and the 60 contact plates 55. If the difference of potential between the brush 54 and one of the contact plates 55 becomes sufficient to cause a spark to leap from one to the other, the current, choosing the path of least resistance 65 will leap the air gap from the finger 60 to

the contact segment which has just been left by the brush 54, causing an additional spark in the cylinder which is making its working stroke and thus avoiding a premature explosion in the succeeding cylinder, such as 70 would occur if the spark were permitted to leap ahead to the contact plate in advance of the brush 54.

It is to be understood that my invention may be embodied in various mechanical and 75 electrical structures and that it is not limited to the precise construction and arrangement of parts illustrated and described herein.

The preferred system of conductors or wiring is shown and described in my Patent 80 No. 838,251.

Having described my invention what I claim and desire to secure by Letters Patent is,

1. The combination with a hydrocarbon 85 engine and an electric ignition apparatus comprising a battery, a generator having a shaft and driven by the engine, and transformer apparatus in circuit respectively with the battery and the generator, of a 90 face plate adapted to rock upon an axis concentric with the generator shaft, a cam wheel on said shaft, and a pair of circuit breakers connected to said face plate and operated by said cam wheel, said circuit 95 breakers being included respectively in the battery and generator circuits, and being movable to advance or retard the spark in the engine.

2. The combination with a hydrocarbon 100 engine, an electric ignition apparatus comprising a battery, a generator having a shaft and driven by the engine, and a transformer apparatus, of a face plate adapted to rock about an axis concentric with the generator 105 shaft, a cam wheel on said shaft adjacent to the face plate and having two cam surfaces, a pair of cam levers operated by said cam surfaces, and circuit breakers operated by said levers, said circuit breakers being 110 respectively in the battery and generator circuits, and said face plate being movable to advance or retard the spark in the engine, for the purpose set forth.

3. The combination with a hydrocarbon 115 engine and an electric ignition apparatus comprising a battery, a generator having a shaft and driven by the engine, a transformer in the battery circuit, and a second transformer in the generator circuit, of a 120 face plate adapted to rock upon an axis concentric with the generator shaft, a cam wheel on said shaft, and a pair of circuit breakers connected to said face plate and operated by said cam wheel, said circuit 125 breakers being included respectively in the battery and generator circuit, and said face plate being movable to advance or retard the spark in the engine.

4. In an ignition apparatus, in combina- 130

tion, an electric generator, a battery, suitable transformer apparatus for the generator and battery, a plurality of contact devices for sending current from either the battery or the generator through the transformer apparatus, and means for simultaneously adjusting the contact devices for advancing or retarding the spark.

5. In an ignition apparatus, in combination, an electric generator, a transformer therefor, a battery and a transformer therefor, a plurality of contact devices for sending current from either the generator or the battery through the primaries of their respective transformers, a spark plug, a single switch for connecting the spark plug in circuit with either of the secondaries of the transformers, and means for simultaneously adjusting the contact devices for advancing or retarding the spark.

10. In an ignition apparatus for a multi-cylinder hydrocarbon motor, the combination of an electric generator, a battery, transformers for the generator and the battery, a plurality of contact devices arranged respectively in the generator and battery primary circuits, a set of spark plugs for the motor, a single distributor having conductors leading to said plugs, means for connecting either of the high tension windings of said transformers to said distributor, and means for simultaneously adjusting the contact devices for advancing or retarding the spark.

15. 7. The combination with a hydrocarbon motor, of an electric ignition apparatus comprising a battery, a suitable transformer for the battery current, a generator driven by the motor, a suitable transformer for the generator current, a member adapted to rock about the axis of the generator shaft, a circuit breaker mechanism and cam means operating same, one of which is mounted on the generator shaft and the other on said

20 member, and said circuit breaker mecha-

nism being adapted to control the primary circuits of both the battery and the generator, and said member being movable to advance or retard the spark in the motor.

8. The combination with a hydrocarbon 50 motor, of an electric ignition apparatus comprising a battery, a transformer for the battery current, a generator driven by the engine, a transformer for the generator current, a member adapted to rock about the 55 axis of the generator shaft, a circuit breaker and a cam for operating same, one of said parts being mounted on the generator shaft and the other on said member and the circuit breaker being arranged in the battery 60 circuit, and a second circuit breaker and a cam for operating same, one of said parts being mounted on the generator shaft and the other on said member and the circuit breaker being arranged in the generator circuit, 65 said member being movable to advance or retard the spark in the engine.

9. The combination with a hydrocarbon engine, of an electric ignition apparatus comprising a battery, a transformer for the 70 battery current, a generator driven by the engine, a transformer for the generator current, a plate mounted on the generator adjacent the shaft thereof, a circuit breaker and a cam for operating same, one of said 75 parts being mounted on the generator shaft and the other on the plate and the circuit breaker being arranged in the battery circuit, and a second circuit breaker and a cam for operating same, one of said parts 80 being mounted on the generator shaft and the other on the plate and the circuit breaker being arranged in the generator circuit.

In testimony whereof I affix my signature in presence of two witnesses.

RUSSELL HUFF.
